UNITED STATES PATENT OFFICE

WILLIAM E. WHITE, OF CHICAGO, ILLINOIS, ASSIGNOR TO KALMAN STEEL COMPANY, OF CHICAGO, ILLINOIS, A CORPORATION OF DELAWARE

LATH CLIP AND METHOD OF INSTALLING THE SAME

Application filed March 1, 1929. Serial No. 343,752.

My invention relates to metal lath and particularly to a novel means of securing the same to furring bars or other supports.

According to common practice, metal lath is attached to the supports by wires projected through the lath and over the support and with its ends twisted. Several clips have also been suggested, in one form of which the ends are interconnected to form a continuous lacing beneath the lath along the line of the support. In another attempt, a single U-shaped spring member is provided with hooked ends which are adapted to be projected through the lath and to spring over the support, the arcuate body portion extending at right angles across the beam or support. In this construction, the lath is held against the support or beam only by the resiliency of the clip, if used for attaching lath beneath the supports and weight is applied thereto, such as the plaster, the lath will sag away from the support to the extent of the bend in the clip. Furthermore, in this form of fastening means, each clip provides but one support, and, consequently, a clip must be installed at each six-inch interval, if this be the required spacing of the lath attachments.

In the interlaced form of attachment, likewise each clip provides but one support and there is consequently not only a waste of material, but more important, of time of the workman in installing the same.

By my structure and method, the objections inherent in the lath clips heretofore proposed are eliminated. The lath is firmly held against the bottom of the furring strip and each clip provides two attachments. By installing the clips in end-to-end spaced relation, I am able to continue the attachments at properly spaced intervals, with a minimum of clips and consequently with a minimum of labor.

The difficulty heretofore experienced in devising a lath clip that would hook over the top of a furring bar or other support and still hold the lath firmly against the bottom of the support, has been overcome by a novel method of installing, which will be more particularly described hereinafter.

The structure will be more readily understood by reference to the accompanying drawings, in which

Fig. 1 is a top plan view of a section of furring bar and lath with my novel clip applied thereto;

Fig. 2 is a bottom plan view thereof;

Fig. 3 is a top plan view showing the clip in an intermediate stage of the installing operation;

Fig. 4 is a sectional view considerably enlarged showing the method of installing;

Fig. 5 is a view similar to Fig. 4 showing the final position of the parts before the withdrawal of the operating tool;

Fig. 6 is a view of the parts in final position; and

Fig. 7 is a perspective view of the wire clip.

In the drawings, I have illustrated a furring bar 10, lath 11 and the lath clip best shown in Fig. 7. The furring bar, while it is shown as of channel form, may be of any preferred shape and many of the principles involved will be utilized in connection with the attachment of the described clip to other forms of supports.

The clip consists of a straight body 12, right angular ends 13 and hooks 14 projecting diametrically oppositely at the two ends of the clip. The hooks are of such dimensions as to insure a secure fit over the top of the furring bar, as best shown in Fig. 6.

The method of installing with the exception of the first step is graphically illustrated in Figs. 3, 4 and 5. In the first step, the lower end as viewed in Fig. 3 is threaded through an opening in the lath and hooked over the top of the support. Thereafter, a pair of pliers 15 is utilized to engage the free end of the clip as indicated in Fig. 4 and the free portion of the clip is rotated or twisted, as permitted by the resiliency of the wire, to cause the hooked end to pass through one of the narrow interstices in the lath. Thereafter, the bent end is moved to the position of Fig. 4 with the end of the body portion a substantial distance away from the side edge of the furring bar and the hooked end in the inclined position shown. By exerting

an upward pressure on the lath by the end of the pliers, the lath and the body of the clip is bent upward until the hooked end lies over the top of the bar. By a rotary movement, the hooked end is then caused to assume the position of Fig. 5 whereupon the pliers are released, and the resiliency of the metal of the parts will cause them to occupy the position of Fig. 6. As shown in this view, the lath is then firmly held against the bottom of the support without dependence upon any stiffness of the metal.

An important point to be noted is that each clip provides two supports and that the clips are spaced apart from end-to-end a distance equal to the required spacing of attachments; that is, approximately six inches.

A workman will very quickly acquire facility in the application of these clips and much time is saved over any known method of attaching lath to supports.

Obviously the construction may be modified to a certain extent, and I do not wish to be limited, except as indicated in the appended claims.

I claim:

1. A lath attaching system comprising in combination with the lath and furring bar, a lath clip composed of resilient material having a straight body and right angularly bent ends terminating in hooks projecting in opposite directions, said hooks having rebent ends, the length of the straight portion of the bent ends being substantially no greater than the combined thickness of the support and lath, the body portion of the clip being adapted to extend diagonally relative to the longitudinal axis of the support and in contact with the lath throughout the length of the clip, with the bent ends extending vertically on opposite sides of the support and the hooks engaging over the support, the bent ends being adapted to be rotated into place, after locally upwardly deflecting the lath and the end of the body portion to the extent of the length of the rebent end of the particular hook that is being positioned.

2. The method of attaching metal lath to supports which consists in associating lath with a support, then projecting one hooked end of a clip through an opening in the lath and engaging the hooked end over the support, then, by rotating the free portion of the clip, projecting the second hooked end through the lath at a point on the opposite side of the support at a distance from the first hooked end equal to the predetermined distance between lath attachments, then while maintaining the second end away from the side of the support, bending the lath sufficiently upward and rotating the hooked end over the support, then releasing the clip and permitting the resiliency of the parts to restore the bent ends to a vertical position alongside the support.

3. The method of attaching metal lath to supports which consists in associating lath with a support, then projecting one hooked end of a clip through an opening in the lath and engaging the hooked end over the support, then, by rotating the free portion of the clip, projecting the second hooked end through the lath at a point on the opposite side of the support at a distance from the first hooked end equal to the predetermined distance between lath attachments, then while maintaining the second end away from the side of the support, bending the lath and body portion of the clip sufficiently upward and rotating the hooked end over the support, then releasing the clip and permitting the resiliency of the parts to restore the bent ends to a vertical position alongside the support.

4. The method of attaching metal lath to supports which consists in associating lath with a support, then projecting one hooked end of a clip through an opening in the lath and engaging the hooked end over the support, then, by rotating the free portion of the clip, projecting the second hooked end through the lath at a point on the opposite side of the support at a distance from the first hooked end equal to the predetermined distance between lath attachments, then while maintaining the second end away from the side of the support, bending the lath sufficiently upward and rotating the hooked end over the support, then releasing the clip and permitting the resiliency of the parts to restore the bent ends to a vertical position alongside the support, and then attaching a second clip in like manner at a distance from the first clip equal to the required spacing of attachments, whereby each clip provides two attachments at spaced points in the length of the support.

In testimony whereof I have affixed my signature.

WILLIAM E. WHITE.
